SCREW CAP LOCKING DEVICE FOR JARS

Rudolf Adolf Isak Lundgren, Sanghus Gard, Overenhorna, Sweden, assignor to Aktiebolaget Astra, Apotekarnes Klemiska Fabriker, Sodertalje, Sweden, a company of Sweden

Filed Nov. 5, 1957, Ser. No. 694,650

Claims priority, application Sweden Nov. 21, 1956

12 Claims. (Cl. 215—43)

The present invention relates to a screw cap locking device for jars. The device according to the invention is characterized in that it consists of a ring of resilient material, said ring being arranged around the jar closely below the screw cap and being non-rotatable in relationship to the jar, and that the ring and the lower edge of the screw cap are provided with coacting serrations, the serration of the ring being able to be disengaged from the serration of the screw cap by the resilient ring being pulled away from the screw cap, which then can be unscrewed.

The locking device will be described in the following with reference to the attached drawing, in which Figures 1 and 2 show two embodiments of the device according to the invention. Fig. 3 shows a locking ring which may replace the locking ring above the bottle in Fig. 2, thereby to include a locking ring having teeth at apparently diametrically opposed points on it.

Figure 1 shows a jar 6, a screw cap 13 and a ring 1 of resilient material. The ring is provided with two diametrically opposed protuberances 2 and 4. In the protuberance 2 there is a notch 3 by means of which the ring is secured to the jar in a way which will be disclosed later. On the top side of the protuberance 4 three upstanding teeth 5 are provided, one side of which extends at right angles to the plane of the ring and the other side sloping to this plane.

In the usual manner the jar 6 is provided with a neck 7 having a thread 12 for the screw cap. The jar turns into the narrower neck by way of the rounded portion 8. Between the portion 8 and the neck there is a collar 11.

On the rounded portion 8 an upstanding shoulder 9 is arranged which is made integrally with the jar itself. This shoulder 9 and the notch 3 of the ring 1 are thus dimensioned that the ring 1 can be put on to the rounded portion 8 in such a way that the shoulder 9 engages the notch 3, whereby the ring 1 is secured against turning.

After the ring 1 has been put on its place, the cap 13 is screwed on. The cap is provided on the lower edge with a serration 18 which is adapted to coact with the teeth 5 on the ring 1 in such a manner that the teeth on the cap snap over the teeth on the ring when the cap is screwed on, whereby the cap can be tightened as desired. The serrations 5 of the ring 1 and serrations 18 of the cap 13 are so shaped that the cap can be screwed onto the jaw 6 against the spring action of the ring 5.

When the cap is to be unscrewed, the lip 4 on the ring 1 is pulled downwards, away from the cap. The teeth 5 then disengage the serration 18 on the lower edge of the cap, whereby the cap is set free and may be unscrewed.

Figure 2 shows a jar 6, and a locking ring 14 somewhat differently shaped. In order to prevent the ring 14 from being turned around the jar, the ring is provided in this case with a protuberance 15 on the out-

2

side of which a recess 16 is arranged, adapted to cooperate with the shoulder 17 which is provided on the rounded portion 8 of the jar, closely below the neck. The protuberance 15 has a thickness increasing towards the periphery so that it abuts the rounded portion of the jar.

In Figure 3, the teeth 5a and the extension 4a adjoining them are located on locking ring 14 apparently diametrically opposite the teeth 5b and the extension 4b adjoining them.

The locking ring should be made of a resilient material. This may be metal but we prefer to make the locking rings of a plastic material, such as polythene. If the material of the ring has sufficient ductility, that part of the ring which carries the teeth 5 will not only be bent downwards, when pressing down the lip 4, but also slip downwards-outwards on the rounded portion 8. The same effect may be attained with a less ductile ring material if the inner diameter of the ring is made so much larger than the outer diameter of the collar 11 of the jar, around which collar the ring is placed, that the ring, when pulling down the lip 4, can be stretched a little while assuming an oval shape.

In using locking rings of a plastic material, especially a fairly soft such a material, it is advisable to make the serration gently rounded off on the ring as well as on the screw cap, this for the purpose of reducing as far as possible the wear of the teeth which will occur when the cap is screwed on.

Possibly the serration may be made in such a manner that the cap can only be screwed on if the lip 4 is kept down. However, from considerations of convenience the embodiment shown is to be preferred, the teeth hence slipping one over the other when the cap is screwed on.

In the embodiment shown the locking ring is fitted with teeth at one point of the periphery only. If desired, teeth may for instance be provided at two diametrically opposed points. Both these portions of the ring must then be pulled down simultaneously in order to release the cap. Such a jar will of course be more difficult to open than that shown in the figures.

As a rule the lower edge of the screw cap need not be toothed all around the periphery. For instance, it may be sufficient to provide teeth along one fourth of the periphery, as usually the variations of the position of the screw cap when fully screwed on are very small.

What I claim is:

1. In combination with a container such as a bottle or jar having (a) a neck closeable by a screw-cap with inside threads that engage in registry with threads on the outside of the container neck and (b) a radially relatively flat shoulder portion of the body of the container annularly encircling the base of the neck, a screw-cap locking means comprising a locking ring whose opening is of such size to slip over the container neck and rest on the relatively flat shoulder portion, and extending from the ring a plurality of teeth shaped to allow correspondingly reciprocally shaped teeth projecting from the bottom of the skirt of the screw-cap to slip over them as the screw-cap is about reaching its closed position and to intermesh and engage with them when the screw-cap reaches its closed position; and, apart from said teeth, holding means on the locking ring adapted to engage with correspondingly reciprocal holding means in the shoulder portion of the container to restrain the locking ring against rotation about the container neck; the locking ring being composed of material yieldable to pressure of at least the engaging teeth of the screw-cap when it tightly engages the locking ring and sufficiently flexible to permit pulling it away to dis-

engage the teeth of the ring from those of the screw-cap thereby to allow the latter to be unscrewed.

2. Locking means in combination as claimed in claim 1, wherein teeth projecting from the bottom of the skirt of the screw-cap are provided on only part of its circumference.

3. Locking means in combination as claimed in claim 1, wherein teeth are provided on only part of the circumference of the locking ring.

4. Locking means in combination as claimed in claim 3, wherein teeth are provided on substantially diametrically opposed parts of the circumference of the locking ring.

5. Locking means in combination as claimed in claim 3, wherein one face of the individual teeth on the locking ring and on the screw-cap is substantially vertical to the plane of their respective bases and the other face of the individual teeth in the locking ring slopes gradually downwardly to its base in the direction in which the cap would be rotated for unscrewing it, and the other face of the individual teeth in the screw-cap slopes gradually upwardly to its base in the direction in which the cap would be rotated for closing.

6. Locking means in combination as claimed in claim 1, wherein the holding means on the locking ring is a recess on it and the reciprocal holding means in the shoulder of the container is a protuberance located adjacent the relatively flat shoulder portion and with its upper part shaped to serve as a male member to engage in registry with the recess on the locking ring.

7. Locking means in combination as claimed in claim 6, wherein the holding means recess in the locking ring extends into an outwardly extending tab-like protrusion of the ring.

8. Locking means in combination as claimed in claim

7, wherein the recess extends from the opening in the ring into the tab-like protrusion.

9. Locking means in combination as claimed in claim 7, wherein the recess extends into the tab-like protrusion from its outer periphery.

10. Locking means in combination as claimed in claim 1, wherein the locking ring has at least one outwardly extending tab-like disengaging protrusion of such length to extend far enough outside of the periphery of the screw-cap in its closed position to enable such protrusion to be grasped between the fingers and pulled outwardly to disengage the teeth on the locking ring from the teeth on the bottom of the screw-cap.

11. Locking means in combination as claimed in claim 10, wherein teeth are provided on only part of the circumference of the locking ring and the disengaging protrusion is located adjacent the teeth in the locking ring.

12. A locking ring for a combination as claimed in claim 1, the opening of which ring is of such size to slip over the container neck and rest on the container's relatively flat shoulder portion, and from which ring there extends a plurality of teeth shaped to allow them to be slipped over by correspondingly reciprocally shaped teeth projecting from the bottom of the skirt of a screw-cap as it is near its closed position and to intermesh with them when it reaches its closed position, said teeth being provided only on a pair of diametrically opposed parts of the ring, and a tab-like disengaging protrusion is located adjacent each of those two toothed parts of the ring 20 and extends outwardly from its outer periphery.
